DETECTOR FINGER AND TIP

Albert Cederlund, Worcester, Mass., assignor to
Crompton & Knowles Loom Works, Worcester,
Mass., a corporation of Massachusetts

Application January 11, 1943, Serial No. 471,994

7 Claims. (Cl. 139—287)

This invention relates to improvements in weft detectors for looms and it is the general object of the invention to provide an improved detector finger and tip so constructed that the tip can be readily removed from the finger when renewal is necessary.

Weft detectors of the side slipping type generally employ a finger or arm having a feeler tip to engage the weft. It is customary to provide some form of indentations or the like which will penetrate a sufficient supply of weft to prevent slipping of the detector arm but which will slide along the bare bobbin when weft is exhausted. Coil springs have heretofore been proposed for use as detector tips but they have been made in such a way that they can either turn to expose the ends of the springs to cause entanglement of the weft, or have required an expensive form of mounting. It is an important object of my present invention to provide a detector tip of the spring type so constructed that the spring is held against rotation with its ends guarded so that they cannot engage the weft.

It is a further object of my present invention to provide the detector arm with a slot across which extends a bridge so constructed that the spring can be threaded over a portion of the detector finger to enter the slot due to the relationship between the coils of the spring and that part of the finger at the end of the slot.

It is another object of my present invention to provide a spring feeler tip having at least one end thereof straightened to provide a prong for entry into a small aperture in the detector finger, the prong and detector finger cooperating to prevent the spring tip from turning on the aforesaid bridge.

Another object of my invention is to provide a spring form of feeler tip in which the resilience of the spring serves to hold the prong in holding relation with respect to the detector finger.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a plan view of a lay, shuttle box and shuttle, and a side slip weft detector provided with a finger and tip made according to my present invention.

Fig. 2 is an enlarged plan view of the detector finger and the tip shown in Fig. 1.

Figs. 3 and 4 are enlarged detail vertical sec-

tions on lines 3—3 and 4—4, respectively, of Fig. 2, and

Fig. 5 is a view similar to a portion of Fig. 2 but showing the manner in which the spring tip can be applied to and removed from a detector finger.

Referring to the drawing, I have shown a lay L having a shuttle box B containing a shuttle S provided with a supply of weft W mounted on the usual bobbin 10. The binder 11 for the shuttle is pivoted to the lay as at 12 and has therein a horizontal slot 13 aligning with a similar slot 14 in the front wall of the shuttle. A support 15 has mounted thereon a weft detector D of the side slipping type provided with a rearwardly extending diagonal detector finger 16. As the lay reciprocates back and forth the weft in the shuttle is presented to the detector and when sufficient weft is present no change in loom operation occurs, but when the weft is exhausted the detector will operate in well-known manner to effect any one of the usual controls, such as bobbin or changing, or loom stoppage.

The matter thus far described is of common construction and is set forth herein for the purpose of illustrating a convenient setting for my invention. I do not wish to be limited to the specific relationship shown in Fig. 1 for the manner in which my invention may be used.

30 In carrying my invention into effect I form the detector finger 16 of flat sheet metal as suggested in Figs. 3 and 4 and form a head 20 on the rear end thereof. A closed vertical transverse slot 21 extending generally in the direction of the length 35 of the shuttle is located within the head and has the end thereof defined by right and left hand walls 22 and 23, respectively, while the rear side of the slot is closed by a bridge 24.

The detector tip is formed of a coil spring 30 40 at least one end of which is straightened to form a prong 31 extending generally in the direction of the length of the slot 21. The wall 23 is provided with a small hole 32 extending therethrough and communicating with the slot 21 and proportioned to receive the prong 31. The spring is preferably slightly longer than the length of the slot, but I have found that this is not an essential relation so long as the spring is of sufficient length to act by its resilience to hold the prong 31 in the hole 32.

When assembling the tip the right end 35 thereof as viewed in Fig. 5 may be sprung over the wall 23 to enter the slot 21 and the spring is then turned to cause it to feed along the bridge 24 until the last coil on which the prong 31 is formed

is within the slot. The spring is then compressed and the prong registered with the hole 32, after which the spring is released so that its expansion will move the prong into the hole 32 to hold the spring against rotation on the barrel.

The end 35 is cut in such relation with respect to the prong 31 that it terminates between the top and bottom of the slot 21. The rear parts of the spring coils serve as teeth to penetrate a sufficient supply of weft to prevent indicating operation of the detector, but when the weft is depleted the spring slides along bobbin 10 to effect a change in loom operation, as already mentioned.

The thread from the delivery eye E of the shuttle extends between the front wall of the latter and the binder 11 and should lie below the detector tip. It occasionally happens that the thread will be high in the shuttle box and slide along the top or bottom surface of the detector finger 16 when the latter enters the shuttle for a detecting operation. Any projection extending above or below the top or bottom surfaces of the detector finger 16 will therefore cause entanglement of the thread with possible breakage. It will be seen by referring particularly to Figs. 3 and 4 that the surfaces which the weft can engage are all smooth or rounded and that the end 35 is guarded by its location within the slot 21, while the prong 31 is received by the opening 32 in the wall 33. Both ends of the spring are therefore held in such position that they cannot engage and entangle the thread and are held in this position due to the fact that the resilience of the spring holds the prong in hole 32 and thus prevents rotation of the spring around the bridge.

I have shown the prong on one end only of the spring and likewise have shown a prong receiving hole in only one of the side walls, namely wall 23, but I do not wish to be thus limited. Whatever the form of the spring tip, its coils will be spaced sufficiently to permit enough compression to allow the prong to enter the hole 32 from the side thereof which opens into the slot 21.

From the foregoing it will be seen that I have provided a simple form of detector tip made of a coil spring having at least one end thereof formed with a prong to enter a part of the detector finger for the purpose of preventing the spring from rotating. It will also be seen that the end 35 of the spring will be held within the slot 21 due to the fact that the spring cannot turn around the bridge 24 as an axis. Furthermore, the spring can be conveniently assembled as indicated in Fig. 5, and can be removed for renewal by a reverse operation, the spring being compressed by movement to the right, Fig. 5, to remove the prong 31 from the hole 32, after which the spring can be turned for unthreading over the wall 23.

Having thus described my invention it will be seen that changes and modifications may be made therein by those skilled in the art without departing from the spirit and scope of the invention and I do not wish to be limited to the details herein disclosed, but what I claim is:

1. A weft detector finger having therein a laterally extending recess located between spaced side walls on said finger, one of said walls having an opening therein, bridge means defining the outer end of said recess and extending from each side wall toward the other wall, and a detector tip comprising a resilient coil spring located between said walls and guided on said bridge means, one end of said spring having a prong thereon

projecting into said opening to prevent turning of the spring on said bridge means.

5 2. A weft detector finger comprising a body from which spaced side walls project rearwardly, bridge means connected to each side wall and defining the outer end of said recess, one of said side walls having an opening therein, and a tip comprising a resilient coil spring surrounding said bridge means and having an end thereof straightened to form a prong to enter said opening and be held therein by the resilience of said spring to prevent turning of the spring with respect to said bridge means.

15 3. A sheet metal weft detector finger having spaced rearwardly extending side walls, bridge means defining the outer end of said recess and extending from each side wall toward the other wall, one of said side walls having an opening therein, and a detector tip comprising a resilient coil spring extending around said bridge means and having one end thereof formed as a prong to enter and be held in said opening by the resilience of the spring to maintain the other end of the spring in a position between the planes of the top and bottom surfaces of the finger.

20 4. A weft detector finger having spaced rearwardly extending walls one of which has an opening therein, bridge means extending from each wall toward the other wall, and a coiled spring detector tip on said bridge means having a prong at one end to enter said opening to operate with said one wall to hold the spring against rotation on said bridge means and with the other end of said spring in front of said bridge means.

25 5. A weft detector finger comprising a body having a closed vertical slot therein so formed as to provide side walls and a rear bridge behind the slot on said finger, and a resilient coil spring surrounding said bridge and having the coils thereof projecting behind the rear surface of the bridge, one end of said spring being formed as a prong and one of said walls having an opening therein communicating with said slot to receive the prong to prevent rotation of the spring around said bridge.

30 6. A weft detector finger comprising a body having a closed vertical slot therein so formed as to provide the finger with lateral walls and a rear bridge behind said slot, and a resilient coil spring surrounding said bridge and having one end thereof terminating between the top and bottom of said slot and having the other end thereof bent to form a projecting prong, one of said walls having an opening to receive said prong and said one wall and prong cooperating to prevent the spring from turning on the bridge and cooperating to maintain the first named end of the spring between the top and bottom ends of the slot.

35 7. A weft detector finger having a vertical closed slot extending through the rear end thereof so formed as to provide side walls and a bridge connecting said walls, and a feeler tip comprising a resilient coil spring surrounding said bridge, one of said walls having an opening therein communicating with the slot and an end of said spring being formed as a prong to enter said opening to prevent turning of the spring on said bridge, the wall opposite said wall having the opening therein engaging the end of the spring opposite the end formed with a prong to assist the spring by the resilience thereof to hold said prong in said opening.

ALBERT CEDERLUND.
